(57) **CLAIM**

The ornamental design for a hygienic undergarment, as shown and described.

DESCRIPTION

FIG. 1 is a perspective view of hygienic undergarment of our new design.

FIG. 2 is a front elevational view thereof.

FIG. 3 is a side elevational view thereof.

FIG. 4 is the opposite side elevational view from that side shown in FIG. 3.

FIG. 5 is an elevational view of the back side thereof.

FIG. 6 is a top plan view thereof; and,

FIG. 7 is a bottom plan view thereof.

The claimed design is broken in two to indicate that no particular length for the drainage tube is claimed.
